UNITED STATES PATENT OFFICE.

ADOLPH BULOVA, OF NEW YORK, N. Y.

DESIGN FOR A TAG FOR WRIST WATCHES.

Application filed November 7, 1924. Serial No. 11,312. Term of patent 3½ years.

To all whom it may concern:

Be it known that I, ADOLPH BULOVA, a citizen of the United States, residing in New York city, in the county and State of New York, have invented a new original, and ornamental Design for Tag for Wrist Watches, of which the following is a specification, reference being had to the accompanying drawing, forming part thereof.

The figure is a perspective view of a tag for wrist watches, showing my new design.

I claim:

The ornamental design for a tag for wrist watches, as shown.

ADOLPH BULOVA.
